UNITED STATES PATENT OFFICE.

FRANZ VON KÜGELGEN, OF HOLCOMBS ROCK, VIRGINIA, AND GEORGE OULTON SEWARD,
OF EAST ORANGE, NEW JERSEY, ASSIGNORS TO VIRGINIA LABORATORY COMPANY,
OF NEW YORK, N. Y., A CORPORATION OF NEW YORK.

HEATING MOLTEN ELECTROLYTES.

1,080,113.

Specification of Letters Patent.

Patented Dec. 2, 1913.

Application filed March 28, 1911. Serial No. 617,432.

To all whom it may concern:

Be it known that we, FRANZ VON KÜGELGEN, a subject of the German Emperor, residing at Holcombs Rock, in the county 5 of Bedford and State of Virginia, and GEORGE OULTON SEWARD, a citizen of the United States of America, residing at East Orange, in the county of Essex and State of New Jersey, have invented certain new and 10 useful Improvements in Heating Molten Electrolytes, of which the following is a specification.

Our invention relates to a method of heating electrolytes in the electrolysis of fused 15 salts and to an improved electrolytic cell adapted thereto.

It relates particularly to a method in which heat other than that supplied by the electrolytic current is employed for maintaining the molten electrolyte at the proper 20 temperature and assisting the electrolytic current.

There are several methods at present in use for heating electrolytes, each of which 25 has certain disadvantages. The method of heating the electrolytic vessel by fuel applied externally has been generally abandoned because of the injurious effects on the vessel and for other reasons. It has been 30 attempted to effect the heating by conducting burning gases onto the surface of the electrolyte, but this has not been successful, and has the disadvantage of contaminating the electrolyte.

35 The general practice at the present time in the electrolysis of molten salts is to rely solely upon the current to perform both functions, heating and electrolysis, but certain advantages in economy of current and 40 establishing proper relation between temperature of the electrolyte and current density can be attained by proper use of a supplementary source of heat.

The object of our invention is to accomplish 45 such supplemental heating without contaminating the electrolyte or injuring the electrolytic vessel.

In the accompanying drawing, which is a vertical section of an electrolytic tank or 50 cell, showing the principle of our invention, the tank is made of a metal shell A lined with a material B not attacked by the electrolyte C. In the electrolyte are immersed the anode D, and the cathode E, the latter

here shown as hollow. On the surface of 55 the electrolyte floats the separated metal F confined by the curtain G. The hollow cathode E is partially submerged in the electrolyte and is provided with a pipe through which enters a burning gas, or a 60 mixture of gas and air, for internally heating the cathode. The drawing shows a gas supply pipe J and an inlet K, so that the device may operate on the principle of the Bunsen burner.

65

L is the pipe through which the gases pass out after having accomplished the heating of the electrolyte through the hollow cathode.

We do not confine ourselves to heating the cathode only, as we may heat the anode 70 or the cathode or both, though generally heat sufficient to replace that lost by radiation from the furnace can be introduced through the heated cathode alone. In the case of the manufacture of sodium we 75 should use an iron cathode and a carbon anode, and we could heat either one or both.

In the drawing we have shown gas as the 80 heating agent, but it is apparent that any other fuel may be used. It is not even necessary to use the hollow electrodes as the heating bodies, since separate heating bodies may be used which can be replaced without interrupting the current. By passing a small current through such separate heating 85 bodies they can be protected from any injurious action of the electrolyte.

In large electrolytic vessels where the 90 radiation losses are not very great, the use of our invention may leave the electric current entirely free to effect electrolysis, the heating bodies replacing all the heat lost by radiation, removal of metal and salt, etc.

We are aware that it has been proposed 95 in the electrolysis of aqueous solutions to heat the electrolyte by a circulation of steam through a coil of pipe lying against the outer wall of the vessel, and serving also as the cathode. Such heating means would not be useful to attain the object of our invention, namely, the maintenance of proper 100 fluidity of the molten salt or compound serving as the electrolyte, and particularly for the production of light metals such as sodium, which when separated 105 float as a molten pool on the surface of the electrolyte. In such electrolysis difficulty is experienced in keeping the bath at

the proper temperature to maintain the requisite fluidity, while yet avoiding over-heating such as would melt down the insulating crust of chilled electrolyte which is 5 ordinarily employed. Our invention by utilizing the high heat of direct combustion within a body which itself is immersed in and surrounded by the molten electrolyte, affords a means whereby the temperature 10 and fluidity of the electrolyte may be controlled to a nicety, the heat of combustion being used merely to supplement the heat resulting from the current used for electrolysis.

15 Having thus fully set forth and illustrated our invention, what we claim is:—

1. An electrolytic cell having a heating means comprising a hollow body immersed in the electrolyte, and means for heating 20 the same by burning a combustible therein.
2. An electrolytic cell comprising a hollow electrode immersed in the electrolyte, and means for heating the same by burning therein a current of hot gas.
- 25 3. The method of supplementing the heating effect of an electrolytic current, which consists in immersing in the electrolyte a hollow body and heating the same by burning a combustible therein.
- 30 4. The method of supplementing the heating effect of an electrolytic current, which consists in immersing in the electrolyte a hollow electrode, and heating the same by

the combustion therein of a current of hot gas.

5. In the electrolysis of molten salts, supplementing the heating effect of the electrolytic current by introducing into the electrolyte a hollow body and heating the latter by burning a gaseous combustible therein. 35

6. In the electrolysis of molten salts, supplementing the heating effect of the electrolytic current by introducing into the electrolyte a hollow electrode, and heating the latter by burning a gaseous combustible 40

45 therein.

7. In the electrolytic production of light metals from molten salts thereof, supplementing the heating effect of the electrolytic current by introducing into the electrolyte 50 a hollow body, and heating the latter by burning a combustible therein.

In witness whereof, I have hereunto signed my name in the presence of two subscribing witnesses.

FRANZ von KÜGELGEN.

Witnesses:

JNO. M. OTEY,
H. C. LIPPERT.

In witness whereof, I have hereunto signed my name in the presence of two subscribing witnesses.

GEORGE OULTON SEWARD.
